UNITED STATES PATENT OFFICE

1,923,983

BULL BOARD FOR RAILWAY STOCK CARS

Lewis Larson and Bernard Burns Tutwiler,
Drummond, Mont.

Application April 29, 1932. Serial No. 608,284

1 Claim. (Cl. 20—22)

The present invention relates to improvements in bull boards for railway stock cars, and has for an object to provide an improved bull board which will be held securely locked in operative position and may be readily unlocked and relocked, promoting great facility in the movement and operation of the bull board and enhancing its security when in operative position.

Another object of the invention is to provide an improved bull board which may with great readiness be removed to an inoperative position leaving the door opening clear for the passage of the cattle.

A further object of the invention resides in providing an improved construction of car door frame for cooperating with the improved bull board, whereby the bull board is operated freely and easily and when in the upper position is received in pockets for retaining same out of the way.

With the foregoing and other objects in view, the invention will be more fully described hereinafter, and will be more particularly pointed out in the claim appended hereto.

In the drawing, wherein like symbols refer to like or corresponding parts throughout the several views,

Figure 1 is a fragmentary side view of a railway stock car with parts in section showing the improved bull board in operative position across the door opening.

Figure 2 is a vertical section taken on the line 2—2 in Figure 1.

Figure 3 is a horizontal section taken on the line 3—3 in Figure 1, and

Figure 4 is a longitudinal section taken through the improved bull board.

Referring more particularly to the drawing 5 represents generally a railway stock car having a side door opening 6, and 7 represents the standards or sills at the sides of the door opening.

In accordance with the invention channel frames are provided in conjunction with the side sills or uprights 7 for the purpose of receiving the improved bull board.

As shown in Figure 3 the sills 7 at outer corner portions thereof are recessed or cut away leaving base portions 8 and shoulders 9 extending at right angles to such base portions. The outer sides of the recessed or cut away portions are removed entirely.

In the recesses are provided channel frames or members having bases 10 fitting against the bases 8 of the recesses and further having inner

flanges 11 and outer flanges 12. The inner flanges 11 are fitted snugly against the shoulders 9; while the outer flanges 12 supply the place of any outer walls for the recesses and confine the bull board at its outer side. Screws or other fastening means 12 are driven through the bases 10 of the channel frames and into the uprights or sills 7.

These channel frames, as more particularly shown in Figures 1 and 2, extend down to a point below the central part of the door opening 6 where the same terminate. The recesses also terminate and filler strips 13 are inserted in the lower portions of the recesses in order to receive and support the lower stop ends 14 of the channel frames.

At the upper portion of the channel frames are provided backwardly and downwardly offset pockets for receiving the lower edge of the bull board. These pockets are formed by wide upper 75 head portions 15 of the channel frame bases 8. The inner flanges 11 are discontinued at the upper portion or are set back into flanges 16 which extend diagonally downward and inwardly of the car whereby to form guides for directing 80 the bull board into the pockets. The diagonal flanges 16 at their lower parts extend forwardly to provide bottom ledges 17 for forming the lower parts of the pockets and constituting rests 85 for supporting the lower part of the bull board.

The forward edges of the pocket bottoms 17 extend below the upper edges 18 of the inner flanges 11 and thus the upper edges 18 form locking means for retaining the bull board in the inoperative position.

The bull board preferably consists of a plank or board 19 of suitable length, breadth and thickness reinforced with sheet metal or other appropriate material. The sheet metal is indicated at 20 as extending over the front face 95 of the board 19 and having the strips 21 and 22 extending over the upper and lower edges of such bull board.

The inner face need not be reinforced nor need the ends of the bull board be reinforced with the metal as such ends do not come in contact with the bases 8 of the channel frame but anti-friction rollers 23, preferably carried in pairs at each end of the bull board are arranged to roll upon the bases 8 to facilitate the raising and lowering of the bull board. These rollers 23 are fitted in slots 24 provided in the ends of the board and the rollers roll upon pintles 25 carried by the board and the metal reinforcing plate 20. Rivets or other appro-

priate fastenings 26 are employed to hold the plate 20 to the bull board 19.

The bull board is latched in its lower operative position by means of the latches 27 pivoted to the uprights or sills 7 as by screws or other fastenings 28. These latches are fan-shaped and provided with outer curved cam edges 29 having stop shoulders 30 for engaging against the bull board to prevent the rotation of the latches in a clockwise direction as looked at in Figure 2.

In the use of the invention the operative position of the bull board is shown in full lines in Figures 1 and 2. In this position the bull board rests upon the bottoms 14 of the channel frame and extends across the door opening 6 at an intermediate point. In this position the bull board is held in place by means of the latches 27.

These latches are simply forced forwardly the full limit of their movement until the shoulders 30 encounter the inner edge of the bull board; whereby the movement of the latches will be arrested. Meantime the cam surfaces 29 have been moved into frictional binding engagement with the upper reinforcing edge of the bull board. The latches will thus be jammed into place. The bull board cannot be raised as the latches cannot be rotated in this direction owing to the position of the pivots 28 and the engagement of the shoulders 30; nor can the latches back off due to the jammed frictional engagement thereof. Thus the bull board will remain locked despite the jarring and shocks incident to travel of the cars. When the bull board is to be raised the latches 27 are forced back to the position shown in dotted lines in Figure 2. The bull board can then be lifted up in the tracks or channel frames until the

same arrives at the uppermost position whereupon the lower part of the bull board is pushed backwardly allowing such lower part to descend into the pockets and to rest upon the ledges 17, being confined by the upstanding ends 18 of the flanges. In this position the bull board will remain without any likelihood of its accidental falling.

When the bull board is to be restored to operative position it is raised so that its lower part will clear the walls 13. The bull board is then moved into a position registering with the channel frames and it may thereupon descend until resting upon the bottoms 14.

It is obvious that various changes and modifications may be made in the details or construction and design of the above specifically described embodiment of this invention without departing from the spirit thereof, such changes and modifications being restricted only by the scope of the following claim.

What is claimed is:—

In combination with a railway stock car having a side door opening, channel frames at the sides of the opening having bottoms, pockets offset rearwardly and downwardly from the upper portions of said frames, rear diagonal flanges for said pockets, downwardly sloping ledges forming bottoms for the pockets, upstanding curbs at the forward portions of the pockets, and a bull board slideable vertically in said frames for resting upon the bottoms and adapted to be canted rearwardly into the pockets back of said curbs.

LEWIS LARSON.
